Attorney

UNITED STATES PATENT OFFICE

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE

RAILWAY CAR HOPPER DOOR

Application filed October 10, 1929. Serial No. 398,624.

The invention relates to railway freight cars, and more particularly to dump cars having a hopper on each side of the center sills of the car and provided with a pair of doors arranged for simultaneous opening or closing of the doors.

An object of the invention is to so form such doors that they will increase the cubical capacity of the car, and at the same time, so dispose the metal that the door will have great strength to retain the load in the car through the medium of the spreader beam whereby the door is relatively light for its strength.

Another object of the invention is to provide such a hopper door with a bulged portion which merges directly into upwardly projecting flanges at certain margins of the door, thereby providing stiffeners and to further stiffen the margins of the door, if necessary, by outwardly reflanging these upwardly projecting flanges.

Another object is to provide an outwardly projecting rib on the hopper set back from the edges of the door opening to stiffen these edges, and furthermore to form a rabbet to engage the flange (and reflange) on the door to form a seal to retard a leak of the lading.

Though the door may be made of a rolled steel plate pressed to form between reciprocating dies, I prefer to make the door of cast metal because a better distribution of the metal for strength requirements can be obtained without the use of separate fixtures, and furthermore, cast metal has greater resistance to corrosion than rolled metal. This last item is important because hopper cars are frequently used to haul coal, which upon becoming moist, forms sulphuric acid which accelerates corrosion.

In the drawings:

Fig. 1 shows a typical door according to my invention with a spreader attached.

Fig. 2 is a section on line 2-2 of Fig. 1.

Fig. 3 is a section on line 3-3 of Fig. 1.

Fig. 4 is a side view of the door shown in

Fig. 1.

Fig. 5 shows a modified construction.

Figs. 6 and 7 show the relation of the door to the car.

The door comprises a main portion 2 formed into a downwardly projecting bulge preferably having its greatest depth adjacent the lower margin of the door, with the surface of the bulge between the place of maximum depth and the lower margin of the door inclined downwardly so as to discharge the lading immediately upon release of the door. The main portion merges directly into an upwardly projecting flange 3 at certain of the edges of the door. These upwardly projecting flanges are preferably positioned at the lower and side margins of the door, but if desired, this flange may be continued around the entire perimeter of the door. This flange overlaps a portion of the hopper 4 of the car, as shown in Figs. 6 and 7, and forms a seal to restrict the escape of the lading.

This flange may be reinforced by the re-flange 6 which preferably projects outwardly from the door and the hopper is preferably provided with an outwardly projecting rib 7 set back from the edges of the hopper door opening which forms a rabbet for the reception of the flange and re-flange on the door. Furthermore, this rib 7 on the hopper 4 stiffens the edge of the door opening and prevents it from being deformed.

A great many cars now in service have a hopper on each side of the center sills, each provided with an opening, which openings are simultaneously closed by a pair of doors connected by a spreader. In my construction I prefer to attach the spreader 9 to the door at its point of greatest depth, as shown in Figs. 2 and 5. This spreader is preferably riveted to the main portion, as shown in Fig. 2, or the door may be provided with a rib 10 to which the spreader 9 may be secured, as shown in Fig. 5. The spreader 9 may be secured to both the main portion and the rib, also shown in Fig. 5. A flat area 11 is preferably provided to furnish a bearing for the spreader to keep it from rocking.

The hinge lugs 12 are preferably cast integral with the door, which in the form illustrated, engage hinge butts 13 attached to the cross ridge 14 of the car. The upper

edge of the door may be provided with a flange 15 positioned under the ridge 14.

The accompanying drawings illustrate the preferred form of the invention, though it is to be understood that the invention is not limited to the exact details of construction shown and described, as it is obvious that various modifications thereof within the scope of the claims will occur to persons skilled in the art.

I claim:

1. A hingeable cast metal door forming part of the load retaining means of a railway car, comprising a main portion formed into a bulge having its greatest depth adjacent the lower margin of the door with the surface of said bulge between the place of greatest depth and said lower margin inclined downwardly.
2. A hingeable cast metal door forming part of the load retaining means of a railway car, comprising a main portion formed into a downwardly projecting bulge having its greatest depth adjacent the lower margin of the door with the surface of said bulge between the place of greatest depth and said lower margin inclined downwardly.
3. A hingeable cast metal door forming part of the load retaining means of a railway car, comprising a main portion formed into a downwardly projecting bulge which merges directly into an upwardly projecting flange at the lower margin of the door.
4. A hingeable cast metal door forming part of the load retaining means of a railway car, comprising a main portion formed into a downwardly projecting bulge which merges directly into an upwardly projecting flange at the lower and side margins of the door.
5. A hingeable cast metal door forming part of the load retaining means of a railway car, comprising a main portion formed into a downwardly projecting bulge which merges directly into an upwardly projecting continuous flange adjacent the perimeter of the door.
6. A hingeable cast metal door forming part of the load retaining means of a railway car, comprising a main portion formed into a bulge having its greatest depth adjacent the lower margin of the door, said door provided with a depending rib at said place of greatest depth.
7. A hingeable cast metal door forming part of the load retaining means of a railway car, comprising a main portion formed into a bulge which merges directly into an upwardly projecting flange at the lower and side margins of the door, said flange being reflanged outwardly.
8. In a railway car, a pair of doors hinged to the body of the car with their hinges in alignment, each of said doors having a main portion formed into a downwardly project-

ing bulge, and a spreader attached to said bulges.

9. In a railway car, a pair of doors hinged to the body of the car with their hinges in alignment, each of said doors having a main portion formed into a downwardly projecting bulge having its greatest depth adjacent the lower margin of the door, and a spreader attached to said bulges at said places of greatest depth.

10. In a railway car, a pair of doors hinged to the body of the car with their hinges in alignment, each of said doors having a main portion formed into a downwardly projecting bulge having its greatest depth adjacent the lower margin of the door and provided with a rib at said place of greatest depth, and a spreader attached to said bulges at said places of greatest depth and to said ribs.

11. In a railway car, a pair of doors hinged to the body of the car with their hinges in alignment, each of said doors having a main portion formed into a downwardly projecting bulge provided with a rib, and a Z shaped spreader attached to said bulges and to said ribs.

12. In a railway car, a pair of doors hinged to the body of the car with their hinges in alignment, each of said doors having a main portion formed into a downwardly projecting bulge provided with a rib, and a spreader attached to said ribs.

13. In a railway car, the combination of a hopper having a discharge opening, and a door hinged adjacent the upper edge of said opening, said door comprising a depressed portion formed in a straight surface of varying depth from the plane of the opening, the lower part of said depressed portion being downwardly inclined toward said plane when the door is in closed position.

14. In a railway car, the combination of a hopper having a discharge opening having forwardly projecting edges, a door hinged adjacent the upper edge of said opening, said door comprising a depressed portion formed in a straight surface of varying depth from the plane of the opening, walls extending from the ends of said depressed portion to said plane, and an upwardly projecting flange at the lower and side margins of the door overlapping the edges of the discharge opening.

15. In a railway car, the combination of a hopper having a discharge opening having forwardly projecting edges, a door hinged adjacent the upper edge of said opening, said door comprising a depressed portion formed in a straight surface of varying depth from the plane of the opening, walls extending from the ends of said depressed portion to said plane, and an upwardly projecting flange at the lower and side margins of the door overlapping the edges of the discharge opening.

opening, said flange provided with a re-flange.

16. In a railway car, the combination of a hopper having a discharge opening having forwardly projecting edges, and an outwardly extending rib set back from said edges, a door hinged adjacent the upper edge of said opening, said door comprising a depressed portion formed in a straight surface of varying depth from the plane of the opening, walls extending from the ends of said depressed portion to said plane, and an upwardly projecting flange at the lower and side margins of the door overlapping the edges of the discharge opening and engaging said outwardly extending rib when the door is in closed position.
17. In a railway car, the combination of a hopper having a discharge opening having forwardly projecting edges, and an outwardly extending rib set back from said edges, a door hinged adjacent the upper edge of said opening, said door comprising a depressed portion formed in a straight surface of varying depth from the plane of the opening, walls extending from the ends of said depressed portion to said plane, and an upwardly projecting flange at the lower and side margins of the door overlapping the edges of the discharge opening, said flange provided with a re-flange engaging said outwardly extending rib when the door is in closed position.

18. In a railway car, the combination of a hopper having a discharge opening, and a door hinged adjacent the upper edge of said opening, said door comprising a depressed portion formed in a straight surface of varying depth from the plane of the opening, said depressed portion having its greatest depth adjacent the lower margin of the door but above the lower edge of the depressed portion when the door is in closed position.
